JOHN F. O'CONNOR, OF CHICAGO, ILLINOIS, ASSIGNOR TO WILLIAM H. MINER, OF CHICAGO, ILLINOIS.

DRAW-BAR-CENTERING DEVICE.

1,178,668.

Specification of Letters Patent. Patented Apr. 11, 1916.

Application filed March 4, 1914. Serial No. 822,404.

To all whom it may concern:

Be it known that I, JOHN F. O'CONNOR, a citizen of the United States, residing at Chicago, in the county of Cook and State of Illinois, have invented a certain new and useful Improvement in Draw-Bar-Centering Devices, of which the following is a full, clear, concise, and exact description, reference being had to the accompanying drawings, forming a part of this specification.

My invention relates to an improvement in draw-bar centering devices for railway cars.

One object of my invention is to provide a cheap and efficient draw-bar centering device.

A further object is to provide a draw-bar centering device in which the spring or compression-resisting member may be placed on one side of the carry-iron, and thus permit the same to be removed from the side of the carry-iron along which train-pipes and other similar train connections are disposed.

In the drawings forming part of this specification, Figure 1 is an elevation plan view of a draw-bar carry-iron and surrounding parts, showing the draw-bar in cross-section, and the draw-bar centering device partly in longitudinal section; Fig. 2 is a plan view of the draw-bar centering device and adjacent parts; Fig. 3 is a section on line 3—3 of Fig. 1.

Referring to the drawings, the numeral 4 represents a draw-bar carry-iron of the usual type and the adjacent parts 5 of a railroad car, to which the draw-bar carry-iron is secured by suitable means, preferably the bolts 6—6. The draw-bar carry-iron 4 is a loop having a horizontal portion 7 upon which the draw-bar 8 is adapted to rest in the usual manner. I provide a plate 23, preferably extending rearwardly from the vertical portions of the carry-iron 9 and having suitable perforations 10 for the passage of the movable bar 11—11 of the draw-bar centering device 12. The bar 11 is provided at its central portion with a saddle 12 of dimensions suitable to permit the draw-bar to rest upon the horizontal portion 7 of the draw-bar carry-iron without disposing of any portion of its weight upon the saddle 12 of the bar 11. The dependent arms 13—13 forming a portion of the saddle 12 are spaced apart to permit the passage of the draw-bar 8 between the same, and in preferable construc-

tion to permit the loose engagement of the draw-bar thereon, as illustrated in Fig. 1 of the drawings. The bar 11 is provided at one end with a preferably smaller portion 14 extended beyond the vertical arm 9 of the draw-bar carry-iron, the said bar being provided near the point of its passage through the plates 23 with a shoulder 15 engaging a spring cap 16 in normal position of the parts, against which is seated a spring 17, the other end of said spring being seated against the outer spring cap 18, which is borne against by the nut 19 threaded upon the outer end of the extension 14 of the bar 11. The said extension 14 of the bar 11, the spring caps and spring are mounted within a spring case 20, the said spring case being suitably secured, preferably by the rivets 21—21, to the adjacent vertical arm 9 of the draw-bar carry-iron. Upon movement of the draw-bar toward the spring case, the bar 11 is actuated in the same direction through the engagement of the draw-bar 8 against the adjacent member 13 of the saddle 12, the shoulder 15 on said bar engaging the spring cap 16, the outward movement of the same the spring 17 against the spring cap 18, which spring cap 18 is held against outward movement by the outer end 24 of the spring case 20. Upon the release of the draw-bar, the same is returned to its normal position through its sliding movement upon the draw-bar carry-iron, and actuated thereon by the expansion of the spring 17, which returns the inner spring cap 16 to its normal position at the inner end of the spring case 20. Upon movement of the draw-bar in a direction away from the spring case, the draw-bar engages against the vertical member 13 of the saddle 12 farthest removed from the spring case, forcing the bar 11 in the same direction, which movement of the bar draws the outer spring cap 18 inwardly, pressing the spring 17 against the inner spring cap 16, which is stopped against inward movement by the shoulder 22—22 at the inner end of the spring case. Upon the release of the draw-bar, the same is returned to its normal position through a sliding movement upon the draw-bar carry-iron, the said movement being actuated by the expansion of the spring 17, which forces the outer spring cap 18 back to its normal position against the outer end of the spring case 20.

I claim:—

In a device of the character described, the combination with a draw-bar carry-iron on which a draw-bar is adapted to be supported so as to have lateral movement, of a draw-bar centering means comprising a bar having a substantially U shaped saddle located intermediate its ends and adapted to extend around a portion of the draw-bar, the sides of said saddle being normally spaced from the sides of the draw-bar, and the oppositely

extending ends of the bar being arranged substantially in the same horizontal plane with the horizontal center line of the draw-bar and having portions on each side thereof, and spring means for resisting movement of said bar in either direction. 15

JOHN F. O'CONNOR.
